[57] CLAIM

The ornamental design for a seat, as shown and described.

DESCRIPTION

FIG. 1 is a front elevational view of the seat comprising my new design;

FIG. 2 is a top plan view thereof;

FIG. 3 is a side elevational view thereof, the opposite side elevational view being a mirror image;

FIG. 4 is a back elevational view thereof;

FIG. 5 is a bottom view thereof;

FIG. 6 is a front elevational view of an alternate embodiment of the seat comprising my new design;

FIG. 7 is a top plan view of the seat of FIG. 6;

FIG. 8 is a side elevational view of the seat of FIG. 6, the opposite side elevational view being a mirror image;

FIG. 9 is a back elevational view of the seat of FIG. 6; and, FIG. 10 is a bottom view of the seat of FIG. 6.
